Filed Jan. 4, 1966, Ser. No. 436

Term of patent 14 years

(Cl. D34—5)

The figure is a perspective view of a bowling ball or similar article showing the new design.

The back of the bowling ball or similar article of the figure is plain.

The essential features of my design reside in the portions shown in full lines and primarily in the concentric circular device located between the finger holes and having two radiating arms extending therefrom and having one arm spaced from the outer circle, but along a radius, and each arm having two small circles; each arm further being spaced equidistantly from the other two arms, all as shown.

I claim:

The ornamental design for a bowling ball or similar article, substantially as shown and described.
